UNITED STATES PATENT OFFICE.

JAMES I. HEALEY, OF BROOKLYN, NEW YORK.

DESIGN FOR FENCES.

Specification forming part of Design No. 6,411, dated February 11, 1873.

To all whom it may concern:

Be it known that I, JAMES I. HEALEY, of Brooklyn, State of New York, have invented certain new and useful Improvements in the Designs for Fences, of which the following is a specification:

The nature of my invention relates to the improvement in the form of iron fences; and consists in, first, the form and configuration of the posts which form part of and support the fence; and, second, the design for the panels, as will hereafter be more fully set forth.

The accompanying illustration fully represents my invention.

a represents round cast-iron posts, having octagonal bases *b*, and octagonal sides *c*, and ornamental head or cap piece *d*. The panels consist of three or more horizontal bars, *e*, made, preferably, of hollow wrought-iron pipes, and joined by the ornamental couplings *g* to the upright picket-bars *i* having the spear

h. In between each bar *i*, and extending up through the two lower bars *e*, are the spindles *l*, which serve to close the spaces between the picket-bars.

The whole forms a neat and tasty design for iron fences, to be used for inclosures of all kinds.

Having thus described my invention, what I claim as new, and desire to secure by Letters Patent, is—

1. The configuration of the posts *a*, as shown.

2. The design for the panels, consisting of the bars *e*, *i*, couplings *g*, and spindles *l*.

3. The design for a fence, consisting of the posts *a*, bars *e*, *i*, couplings *g*, and spindles *l*.

JAMES I. HEALEY.
